PAINT BRUSH GUARD

John Maslaney, Marquette, Mich.

Application July 20, 1956, Serial No. 42,308

Term of patent 14 years

(Cl. D9—2)

Fig. 1

Fig. 2

Fig. 3

Fig. 5

Fig. 4

Fig. 1 is a perspective view of a paint brush guard embodying my new design;

Fig. 2 is a top plan view thereof;

Fig. 3 is a side elevational view thereof;

Fig. 4 is a cross-sectional view taken along the plane IV—IV of Fig. 2; and

Fig. 5 is a cross-sectional view taken along the plane V—V of Fig. 2.

The dotted lines are for the purposes of illustration only.

I claim:

The ornamental design for a paint brush guard, as shown and described.
